Atty.

UNITED STATES PATENT OFFICE.

ALBERTO VEZZANI, OF GENOA, ITALY.

CARTRIDGE FOR FIRE EXTINGUISHERS.

Application filed December 21, 1923, Serial No. 681,902, and in Italy December 30, 1922.

There exist self-acting fire extinguishers in which, upon the breaking of a receptacle containing one of the two chemical reagents capable of producing the development of a gas, the two reagents are brought into contact in a reaction chamber, generally known as "cartridge", the gases which are developed escaping from said cartridge and exerting a pressure upon the inert liquid contained in the fire extinguisher and expelling said liquid in the shape of a violent jet.

It is also known to provide the cartridge with means through which the generated gas passes, before it is expelled into the reservoir, to render the gas dry and non-acid.

The present invention relates to a cartridge of the aforesaid kind provided with an improved filtering means adapted to prevent the fire extinguishing liquid from becoming mixed with a more or less considerable quantity of the residues of the gas generating materials contained in the cartridge, which residues, in the case of being conveyed off by the gas developed, would diminish the degree of dielectricity of the jet and consequently expose the operator to danger when extinguishing fires caused by high tension currents.

In the annexed drawing, diagrammatically illustrating an embodiment of the invention:

Fig. 1 is a main central section of a fire extinguisher containing a cartridge provided with said improved filtering means;

Fig. 2 is a separate sectional view of the cartridge with the improved filtering means on a larger scale.

According to Fig. 1, the fire extinguisher comprises a can 1 airtightly sealed by a closure 2; a pipe 3 which starting from the bottom of the can terminates in the discharge hole 4 provided in the upper portion of that wall of the can which is opposite the handle 5; a striker 6 passes through the center of the closure 2.

The apparatus is provided with a safety handle 9 which keeps the striker lifted, closes the discharge hole by means of the tongue piece 10 and enables the apparatus to be suspended or to be carried by hand.

Upon the handle is sealed the safety wire 11 fastened to the striker.

Inside the can is arranged a cartridge formed of a cylindrical outer casing 15 having at the upper portion a flange 13, by means of which it rests in a notch 14 provided in the mouthpiece of the can.

Inside the casing 15 and at the upper portion of it is suspended a cup 16 having the shape of a truncated cone and airtightly sealed by means of a disc 17.

Inside the cup is arranged another truncated cone 18, provided with holes 19, which cone at the moment of the blow of the striker facilitates the perforation of the disc 17 and simultaneously causes the bottom of the cup to get detached.

In the space 27 between the outer side of the truncated cone 18 and the inner side of the cup 16, and also inside the truncated cone 18 is contained the chemical compound which, by reacting with the other compound contained inside the casing 15, causes the development of the pressure gas.

According to the nature of the substances employed, the solid reagent may be contained in the cup 16 and the liquid one in the casing 15 or conversely.

The peculiar shape of the cup 16 allows the reagent to be completely discharged into the casing 15 arranged thereunder containing the other reagent, with the result of the immediate starting of the chemical reaction.

From the flange 13 of the casing 15 a double walled jacket projects downward enclosing the cartridge and formed of an outer tube 28 surrounding the casing 15 and an inner tube 32 open at the bottom.

The tube 28 is provided with discharge openings 29, at the top, to communicate with the can 1, while the upper portion of the casing 15 is provided with holes 21 which permit the cartridge to communicate with the space 30 between said casing and the tube 32 upon the breaking of the disc 17.

To charge the apparatus the stuffing box 8 is unscrewed, the closure 2 is removed and the extinguishing liquid, such as tetrachloride of carbon, is poured into the can, thereupon the cartridge is introduced into the receptacle and lastly the cover 2 is again set up.

If the apparatus charged is not to be used at once, the safety handle 9 is turned up so as to keep the striker in the lifted position and the discharge hole 4 obstructed by the tongue piece 10; after that, the safety wire 11 is sealed upon the handle in order to render immovable the striker. In this condition, the apparatus may be suspended to a stationary support.

When the fire extinguisher is to be made use of, the safety handle is turned down

and then a violent blow is struck against the striker.

Through the turning down of the handle, the safety wire 11 breaks, the discharge hole 4 is uncovered and the striker 6 is set free. The striker being hit breaks the disc 17 and presses downward the truncated cone 18 which, as already stated, causes the bottom 20 to become detached and the two reagents 10 to come in contact with each other.

The gas produced by the reagents contained in the cartridge passes through the holes 21 into the intervening space 30 existing between the sealing box and the jacket, follows the direction indicated by arrows (Fig. 2), ascends again in the space 31 between the two walls of the jacket and lastly upon having passed through the holes 29 of the jacket exerts its pressure upon the fire 20 extinguishing liquid contained in the can 1.

The two spaces 30 and 31 together form the gas purification chamber; the residues, which may be produced by the reagents, during the travel are deposited in the said 25 chamber so that the gas escaping through

the holes 29 will be completely free from impurities.

The jacket may form an integral portion of the cartridge or it may be detachable from the cartridge so as to facilitate the 30 cleaning of the purification chamber after the use of the fire extinguisher.

I claim as my invention:

A cartridge for fire extinguishers, comprising an outer wall, a flange provided 35 thereon, and a double walled jacket formed of two co-axial tubes, an outer and inner tube, projecting from said flange, the said tubes being spaced from each other and from said outer wall, the space between said inner tube and said outer wall communicating with the cartridge through holes provided at the top of said outer wall, the space between said inner and outer tubes being open to the outside of said outer tube, said inner 40 tube being open at its free end.

In testimony whereof I affix my signature this seventh day of December 1923.

ALBERTO VEZZANI.
